UNITED STATES PATENT OFFICE.

ELVER H. SHAW AND JUSTIN D. WIXOM, OF CLAY CENTRE, KANSAS.

DOOR-CHECK.

SPECIFICATION forming part of Letters Patent No. 361,840, dated April 26, 1887.

Application filed December 21, 1886. Serial No. 222,212. (No model.)

To all whom it may concern:

Be it known that we, ELVER H. SHAW and JUSTIN D. WIXOM, both of Clay Centre, in the county of Clay and State of Kansas, have invented a new and Improved Door-Check, of which the following is a full, clear, and exact description.

Our invention relates to a check for holding doors or gates open, and has for its object to provide a simple, inexpensive, and effective device of this character which is adapted for use with either right or left hand doors or gates, and will operate easily, quietly, and automatically as the door or gate is opened to hold it open, and may be readily disengaged to allow the door to be closed.

The invention consists in certain novel features of construction and combinations of parts of the door-check, all as hereinafter fully described and claimed.

Reference is to be had to the accompanying drawings, forming a part of this specification, in which similar letters of reference indicate corresponding parts in all the figures.

25 Figure 1 is a perspective view of the interior of a room, showing our improved door-check in operative position. Fig. 2 is a front elevation of the main parts of our door-check. Fig. 3 is a plan view thereof. Fig. 4 is an end view of the parts shown in Fig. 2, with the catch-plate, which is shown in vertical section. Fig. 5 is a front view of the catch-plate; and Fig. 6 is a plan view of the catch-plate, with the end of the latch indicated in dotted lines.

35 The door-check comprises a latch device, A, to be attached to the base-board or wall, and a catch, B, which is to be attached to the face of a door, as shown in Fig. 1 of the drawings, and whereby as the door is opened its catch 40 will be automatically engaged by the latch, as hereinafter more fully explained.

The latch device is made preferably with a base-plate, C, having a lug, c, to which the latch-bar D is pivoted at its inner end by a pin, 45 E. The outer end of the latch-bar is formed as a hook, d, which is adapted to engage a recess, b, in the upper face of the catch B, as shown in Fig. 4 of the drawings, and the pivoted end of the latch-bar is formed with a shoulder, e, which, by striking the base-plate C, prevents fall of the bar below a horizontal position.

A lever, F, which is pivoted at f, about at its center, to the base-plate C, is bent outward at one end, and thence parallel with the base-plate, 55 to form a pin, f', which enters a hole, d', made in the latch-bar D, and the opposite end of the lever is also bent or shaped with a projection, f'', which is preferably serrated or roughened at both upper and lower faces, to prevent easy 60 slip of the foot from it in operating the door-check to release the door, as presently described. Lugs G H, cast on the base-plate, form stops to limit the depression of the lever, and consequently the rise of the latch-bar, when 65 disengaging the bar from the catch-plate.

As shown most clearly in Figs. 5 and 6 of the drawings, the catch-plate B has a semicircular form at its front part, and its recess b has a like form at its outer edge or wall, and the 70 outside face of the semicircular front of the plate is beveled or rounded over, as at b', to allow the beveled or inclined face d' of the latch-bar hook d to readily engage with the catch-plate by riding over its face b' and dropping 75 into the recess b.

The operation of the device is very simple and effective, and as follows: When the door I, to which the catch-plate B is fixed, is opened, the catch-plate will lift the latch-bar so its hook 80 d will automatically engage the catch-plate by dropping into its recess b, as in Fig. 4, and the door will be held open. To close the door, a person will press on the end f' of the latch-lever with the foot, which will lift the hook d 85 from the recess b and allow the door to be swung shut. The horizontally-rounded front of the catch-plate and its correspondingly-shaped recess allow the engagement of the latch-bar with the catch-plate not only when 90 the base-board or wall to which the latch A is fixed is in the same plane with the closed door, but also when the latch is fixed to a wall standing at right angles to the closed door or at any intermediate angular position, and as 95 will be understood from the dotted position of the latch-bar in Fig. 6 of the drawings.

It is obvious that by removing the pivot E of the latch-bar and turning the bar upside down, and turning the base-plate, to which the 100 latch-bar is again pivoted, the other edge up when attaching it to the base-board or wall, the latch may be used to catch and hold doors opening either to the right or left hand, the

operation being practically the same in either case. The latch-plate C and flanges on the catch-plate B are perforated to receive fastening screws or nails for securing them in operative positions.

Among the advantages of our door-check may be named the following: It may be used to hold outside or barn doors or gates, and will prevent the wind blowing them shut. It may be used with light doors—such as screen or glazed doors—without danger of racking or springing them out of shape, as the engagement of the latch with the catch is very easily effected, and, withal, without jar or noise. Furthermore, the door-check is clear of the floor and does not interfere with carpets or other floor-covering, and there are no springs or other fragile parts to the check which are liable to be easily broken or to get out of order, and, finally, the entire device is very easily made and at a trifling cost, and may be applied and operated by any person of ordinary intelligence.

Although the drawings represent the preferred form of device, the base-plate C may be dispensed with without departing from the spirit of our invention, and in this case the latch-bar D and lever F would be pivoted directly to the base-board or wall or fence, as the case may be, and in relatively operative positions above described.

Having thus described our invention, what we claim as new, and desire to secure by Letters Patent, is—

1. In a door-check, the combination, with the base-plate C, provided with the lug c and the stops G H and a catch-plate, of the hook D, pivoted to the lug c and provided with the hole d', and the lever F, pivoted to the plate C and provided with the pin f', entering the aperture d' in the hook, substantially as herein shown and described.

2. In a door-check, the combination, with the semicircular catch-plate B, having a correspondingly-shaped recess, b, in its upper face, of the plate C, the hook D, pivoted to the plate C and provided with the aperture d', and the lever F, pivoted to the said plate C and provided with the pin f', fitting in the aperture of the hook, substantially as herein shown and described.

3. The catch-plate B, of semicircular form and having a correspondingly-shaped recess, b, in its upper face, and beveled edges b', substantially as herein shown and described.

ELVER H. SHAW.
JUSTIN D. WIXOM.
